UNITED STATES PATENT OFFICE.

EDWARD C. STERLING, OF BEAVER FALLS, PENNSYLVANIA.

PHOTOGRAPHIC-PRINTING DEVICE.

1,230,532.

Specification of Letters Patent. Patented June 19, 1917.

Application filed February 26, 1916. Serial No. 20,669.

To all whom it may concern:

Be it known that I, EDWARD C. STERLING, a citizen of the United States, residing at Beaver Falls, in the county of Beaver and State of Pennsylvania, have invented a new and useful Photographic-Printing Device, of which the following is a specification.

This invention relates to photographic printing devices and has more especial reference to a device of this character in which photographic prints may be quickly and easily made with the use of a small amount of light.

The object of this invention is to provide a photographic printing device of the character referred to, which will throw a diffused and even light upon all parts of the negative and paper upon which the print is made.

A further object is to provide a device of this character in which the lamp within the device is automatically lighted as the device is closed and automatically extinguished as the device is opened.

A still further object is to provide such a device in which prints may be quickly and readily made.

With these objects in view the invention consists in the novel construction and arrangement of parts, hereinafter described, illustrated in the accompanying drawings, and particularly pointed out in the appended claims, it being understood that various changes in the form, proportions, size and minor details of construction may be made within the scope of the appended claims without departing from the spirit or sacrificing any of the advantages of the invention.

In the accompanying drawing:

Figure 1 is a perspective view of a photographic printing device constructed in accordance with my invention.

Fig. 2 is a vertical section of the same, showing the device in a closed position.

Fig. 3 is a top plan view of the same.

Fig. 4 is a side elevation showing the device in the opened position.

Similar numerals of reference indicate corresponding parts throughout the several figures of the drawing.

Referring more especially to the construction illustrated in the accompanying drawings, the numeral 1 indicates a receptacle formed of wood or other suitable material, said receptacle being shown in the drawings

as forming the frustum of an inverted pyramid. This receptacle may be of any other suitable form, however, it has been found that better results are obtained by tapering the receptacle toward its lower extremity. A frame 2 is provided around the upper open extremity of the receptacle 1, said frame being provided with a central aperture 3, a strip 4 being provided along the rear edge of said frame.

A cover is provided upon the frame 2 and is adapted to cover the central opening 3 thereof and extend beyond the edges of said opening, said cover being substantially the same as the cover or back of the ordinary photographic printing frame and comprising the members 5 and 6, which are hinged together by means of hinges 7, a coil spring 8 being connected to the hinged edges of each of said members and adapted to normally hold said members in the relative position to each other as indicated in Fig. 4 of the drawing.

The rear member 5 of the cover is hinged to the strip 4 by means of double hinges 9, said double hinges allowing a slight vertical adjustment of the cover in order to accommodate negatives and paper of varying thickness.

A block 10 is mounted upon the strip 4 intermediate the extremities thereof and connected to said block by means of the hinge 11 is the operating handle 12. The hinge 11 is provided with a coil spring 13 adapted to normally hold the operating handle in contact with the spring bumper 14 as shown in Fig. 4 of the drawings and the forward extremity of the forward cover member 6 is hinged to the operating handle by means of a double hinge 15. A pair of spring pressure arms 16 are provided upon the operating handle 12 and adapted to contact with the cover to hold the same firmly in engagement with the negative and printing paper when the device is in the closed position.

The usual glass 17 may be provided in the shoulder or recess 18 located around the central aperture of the frame 2 when it is desired to print from the usual kodak films or if it is desired to print from the ordinary plates the glass may be removed and the plate located within the recess 18. A sheet of translucent material, preferably finely ground glass 19, is located beneath the frame 2 and covers the central aperture 3 of

said frame. The tapered side walls of the receptacle 1 are provided upon their inner faces with mirrors 20, the reflecting surfaces of said mirrors being preferably provided with a ground glass finish.

5 The lower extremity of the receptacle is closed by the wall 21 and a high power electric lamp 22, preferably an incandescent nitrogen bulb, is located upon said lower wall, a small ruby light 23 being also provided upon said wall. Wires 24 and 25 leading from a suitable source of electrical supply are connected to the ruby lamp 23, the wire 24 passing through the lamp 22 and being connected to a spring contact arm 26, the wire 25 leading from the ruby lamp to a contact plate 27 adapted to be engaged by the spring arm 26. This spring switch member is located in a socket 28 formed in 10 the forward portion of the frame 2 and a finger 29 is carried upon the under surface of the operating handle 12 and adapted to engage the spring arm 26, when the operating handle is moved into the closed position as shown in Fig. 2, thus moving said spring arm into engagement with the contact plate 27 and closing the circuit through the lamp 22.

15 A suitable pad 30, of felt or the like, is provided upon the under surface of each of the cover members 5 and 6, said pad being of the ordinary construction. When the device is in the normal position as shown in Fig. 4 the spring 13 in the hinge 11 tends to hold the operating handle 12 in engagement with the spring bumper 14 and the coil spring 8 holds the members 5 and 6 of the cover in the position shown in said figure. The spring switch which controls the 20 circuit to the lamp 22 will be open at this time. When it is desired to make a print the film and paper are placed together in the usual manner upon the glass 17 and may be held in position with one hand while 25 with the other hand the operator moves the handle 12 down until the member 5 of the cover engages the film and paper holding the same against relative movement. The handle may then be moved to the position shown in Fig. 2, the finger 29 thereon closing the circuit to the light, the mirrors 20 reflecting a diffused light evenly to all parts of the film or negative. When the print has been exposed the proper length of time the 30 operating handle is released and the spring 13 in the hinge thereof will throw the handle and cover into the position shown in Fig. 2, the operating handle contacting with the spring bumper 13 and preventing any sudden jarring of the several parts of the device.

35 Although the drawings and above specification disclose the best mode in which I have contemplated embodying my invention 60 I desire to be not limited to the details of

such disclosure, for, in the further practical application of my invention, many changes in form and construction may be made, as circumstances require or experience suggests, without departing from the spirit of the 70 invention within the scope of the appended claims.

I claim:

1. A device of the character described comprising a receptacle, a lamp located in 75 said receptacle, means at the upper extremity of said receptacle adapted to receive a negative and a sheet of sensitized paper, a hinged cover upon said receptacle adapted to clamp the negative and paper in position, 80 said cover comprising a member hingedly connected to said receptacle and a second member hingedly connected to the free edge of said first member, and an operating handle hingedly connected to said receptacle 85 and hingedly connected to the free edge of said second hinged member.

2. A device of the character described comprising a receptacle, a lamp located in 90 said receptacle, means at the upper extremity of said receptacle adapted to receive a negative and a sheet of sensitized paper, a hinged cover upon said receptacle adapted to clamp the negative and paper in position, said cover comprising a member hingedly 95 connected to said receptacle and a second member hingedly connected to the free edge of said first member, an operating handle hingedly connected to said receptacle and hingedly connected to the free edge of said 100 second hinged member, and means for normally holding said cover in the raised position.

3. A device of the character described comprising a receptacle, a lamp located in 105 said receptacle, means at the upper extremity of said receptacle adapted to receive a negative and a sheet of sensitized paper, a hinged cover upon said receptacle adapted to clamp the negative and paper in position, 110 said cover comprising a member hingedly connected to said receptacle and a second member hingedly connected to the free edge of said first member, an operating handle hingedly connected to said receptacle, the 115 free edge of said second member being hingedly connected to said handle, a spring arranged to hold said handle normally in raised position and a bumper arranged to contact with said handle in the raised position.

4. A device of the character described, comprising a receptacle, a lamp located in 120 said receptacle, means at the upper extremity of said receptacle adapted to receive 125 a negative and sheet of paper, a hinged cover upon said receptacle adapted to clamp the negative and paper in position, said cover comprising a member hingedly connected to said receptacle and a second mem- 130

ber hingedly connected to the free extremity of said first member, an operating handle hingedly connected to said receptacle and to the free edge of said second member, a 5 spring arranged to normally hold said handle in raised position, a second spring at the joint between said cover members arranged to cause the second member to contact with the paper before the first member 10 and a bumper arranged to contact with said handle in the raised position.

5. A device of the character described, comprising a receptacle, a lamp located in said receptacle, means at the upper extremity of said receptacle adapted to receive 15 a negative and sheet of paper, a hinged cover upon said receptacle adapted to clamp the

negative and paper in position, said cover comprising a member hingedly connected to said receptacle and a second member 20 hingedly connected to the free edge of said first member, an operating handle hingedly connected to said receptacle and to the free edge of said second member, spring pressure arms upon said handle arranged to contact with said cover members, a spring connected to said handle to normally hold said handle in the raised position, and a bumper arranged to contact with said handle in the 25 raised position.

In testimony that I claim the above, I have hereunto subscribed my name.

EDWARD C. STERLING.
